UNITED STATES PATENT OFFICE.

WILLIAM H. MINER, OF CHAZY, NEW YORK.

DRAFT-RIGGING FOR RAILWAY-CARS.

1,222,118.

Specification of Letters Patent. Patented Apr. 10, 1917.

Application filed April 18, 1914. Serial No. 832,688.

To all whom it may concern:

Be it known that I, WILLIAM H. MINER, a citizen of the United States, residing at Chazy, in the county of Clinton and State 5 of New York, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is, to provide 15 a draft rigging of high capacity and efficient operation.

In the drawings forming a part of this specification, Figure 1 is a side elevation, partly in vertical longitudinal section, of a 20 draft rigging embodying my invention, and illustrating the parts in normal position; Fig. 2 is a horizontal section along line 2—2 of Fig. 1, but illustrating the position of the parts when in full buff; Fig. 3 is a cross 25 section on line 3—3 of Fig. 1.

Referring to the drawings, the numerals 5—5 indicate draft members or parts of the car-frame to which the draft rigging is applied. Upper and lower stop members 6 and 7, respectively, are secured between the draft members, each of the stop members 30 consisting of a preferably channel-shaped member 8 having a horizontal web 9, and at either edge a longitudinally extending flange 10. The flanges 10 of the upper member are preferably up-turned, and those of the lower stop member preferably down-turned rivets 11—11 passing through the flanges 10 and the adjacent draft member, securing the 35 stop members between the draft members. Each stop member is provided intermediate its ends with a vertical opening 12, the edges of the members 6 and 7 forming the ends of each opening 12 being preferably in-turned, 40 forming at the forward end an upper stop shoulder 13 in the upper stop member, and a lower stop shoulder 14 in the lower stop member, at the rear end forming an upper shoulder 15 in the upper stop member, and 45 a lower stop shoulder 16 in the lower stop member. Between the upper and lower stop members 6 and 7, respectively, are mounted 50 the side links 17—17, the rear connecting side links 17—17, the rear connecting lateral slots 19—19 key 18 passing through lateral slots 19—19 55 near the rear ends of the link 17, the ends of the key 18 extending through longitudi-

nally extended slots 20—20 in adjacent portions of the draft members to permit longitudinal movement of the key 18 therein. At 60 their forward ends the links 17 are provided with transverse slots 21—21 to receive the coupler key 22, which passes through the transverse slot 23 in the draw-bar 24, and has its ends received in longitudinally extending slots 25 formed in adjacent portions 65 of the draft members 6 to permit the longitudinal movement of the key 22 in said slots. The slots 21 near the forward ends of the links 17 are rearwardly extended to 70 permit the rearward travel of the key there-in on buffering movement of the draw-bar. Between the draft members and within the openings 12 in the stop members is mounted a front follower 26 and a draft gear 27. The draft gear comprises a shell 28 having 75 a spring-cage 29, preferably at its rear end, and a friction case 30, preferably at its forward end, and preferably integral with the spring case 29. Within the spring case is mounted, in vertical twin arrangement, the 80 spring elements 31, the said spring elements being preferably in two sets, the upper set 32 comprising the outer spring 33 and the inner spring 34 nested therein, the lower set 35 preferably comprising the outer spring 85 36 and the inner spring 37 nested therein. A slot 38 extends transversely through the spring-cage and between the upper and lower sets of springs for the passage of the rear key 18, said key being adapted to support the draft gear between the draft members. At its rear end, the shell is provided 90 with a preferably integral plate 48 adapted to engage against the rear stop shoulders 15 and 16. The sets of springs are seated 95 at their rear ends against the forward face of the plate 48, and at their front ends against the movable spring seat 39. The movable spring seat engages against the friction elements 40 within the friction shell 100 30, the friction elements including preferably the friction shoes 41 and a wedge 42 adapted to spread the same. In preferable construction, in normal position of the parts 105 of the gear and in buffering action, the rear key 18 engages the rear ends of the slots 20 in the draft members simultaneously with the engagement of the shell 28 against the rear stop shoulders 15 and 16, and also simultaneously the front edge of the slot 38, 110 through the spring-cage, engages the front edge of the key 18.

On rearward movement of the draw-bar, the shell is in engagement against the rear stop members 15 and 16; the draw-bar forces the front follower rearwardly, compressing the friction elements and spring elements within the shell. The shell is stopped against rearward movement not only by the rear stop shoulders, but preferably also by the rear key 18.

10 On forward movement of the draw-bar, the coupler key is drawn forwardly, and through its engagement with the draft links at the forward ends of the slots 21-21 therein, the draft links are drawn forwardly, forwardly actuating in turn the rear key 18, which key draws the shell forwardly, bringing the friction elements and spring elements within the shell into compression resisting action.

20 I claim:

1. In a draft rigging for railway cars, the combination with draft members, draw-bar, draft links and a key connecting the draft links to the draw-bar, of stop mem-

bers, a friction shell having friction elements therein, a spring case secured to said shell, the spring case having vertically twin arranged springs therewithin, and a transversely extending key, the key passing through the case and between the springs, 30 through the draft links and through the draft members.

2. In a draft rigging for railway cars, in combination, draft members, a draw-bar, draft links, a coupler key connecting the 35 draft links to the draw-bar, stop members secured to the draft members, a shell, friction elements and spring elements within the shell, the spring elements being in vertical twin arrangement, the key passing 40 through the draft links, the shell, and the draft members, and being interposed between the spring elements in the shell.

WILLIAM H. MINER.
